(57) **CLAIM**

The ornamental design for a fishing lure, as shown and described.

DESCRIPTION

FIG. 1 is a perspective view of a fishing lure in accordance with one embodiment of the invention, showing the top, front and left side of my new design;

FIG. 2 is a right side elevation view thereof;

FIG. 3 is a front elevation view thereof;

FIG. 4 is a rear elevation view thereof;

FIG. 5 is a top plan view thereof; and

FIG. 6 is a bottom plan view thereof.

FIG. 7 is a perspective view of a fishing lure in accordance with a second embodiment of the invention, showing the top, front and left side of my new design;

FIG. 8 is a right side elevation view thereof;

FIG. 9 is a front elevation view thereof; and,

FIG. 10 is a top plan view thereof.

The broken-line showings of the hooks, hook eyes and fish eyes are for illustrative purposes only and form no part of the claimed design.
